UNITED STATES PATENT OFFICE.

STEPHEN EDWARD PARKS, OF PORTLAND, NORTH DAKOTA, ASSIGNOR OF ONE-HALF TO
T. H. ARNOLD, OF PORTLAND, NORTH DAKOTA.

SASH-BALANCE.

No. 901,553.

Specification of Letters Patent.

Patented Oct. 20, 1908.

Application filed June 24, 1907. Serial No. 380,537.

To all whom it may concern:

Be it known that I, STEPHEN EDWARD PARKS, a citizen of the United States, residing at Portland, in the county of Traill, State 5 of North Dakota, have invented certain new and useful Improvements in Sash-Balances; and I do hereby declare the following to be a full, clear, and exact description of the invention, such as will enable others skilled in 10 the art to which it appertains to make and use the same.

This invention relates to sash balances and has for its object to provide a device of this 15 class which serves to hold either of the sashes of a window at any elevation to which they are raised or lowered as the case may be.

I have in view the provision of a spring controlled device of this class which, while simple in construction, will at all times be 20 effective and will not bind under any circumstances.

In the accompanying drawings, Figure 1 is a front elevation of a window showing my device in use, parts of the window sash being 25 broken away to more clearly show the invention, Fig. 2 is a detail vertical sectional view taken through one of the stiles of the sash and the corresponding stile of the frame, Fig. 3 is a similar view but taken in a horizontal plane, the device being shown however in top plan, and, Fig. 4 is a detail perspective view of the friction element of the device removed from its socket.

In the drawings, there is shown a window 35 sash including a stile 5 and a window frame in which the sash is mounted, the stile of the frame being indicated by the numeral 6.

Formed in the stile 5 of the window sash are a number of bores or sockets 7 which open 40 into countersinks 8 also formed in the said stile and in the edge face thereof. Seated in the bore 7 is a socket 9 which is cylindrical in form and has its open end flush with the inner wall of the countersink 8 and received in 45 this socket is a stud 10 which is formed integral with the rear face of a friction plate 11. A spring 12 is also seated in the socket and this spring bears against the inner or closed end of the socket and against the inner end 50 of the stud 10 and thereby serves to force the

stud and the friction plate carried thereby outwardly and against the face of the stile of the window frame mentioned above. The ends of this friction plate are curved inwardly slightly as at 13 so as not to bite into 55 the window frame stile and thereby cause binding of the balance.

From the foregoing it will be readily understood that under all conditions and at all times, the friction plate is held tightly 60 against the face of the stile of the window frame and that consequently the sash will be held to bear against the other stile of the window frame, the sash being held by this means at any point in its sliding movement. 65 Furthermore the sash will be in this manner prevented from rattling in windy weather.

As shown in the drawings, the devices are located at one side of the window sash only and consequently the result above men- 70 tioned will be attained.

What is claimed, is—

In a device of the class described, the combination with a window sash stile and the corresponding stile of the window frame, the 75 sash stile being provided with a countersink and with a bore opening into the countersink, of a friction plate, the said plate having its upper and lower ends turned bodily inwardly, a stud formed integral with the inner 80 face of the friction plate at a point mid-way of its said ends, the ends resting at their extremities normally against the inner wall of the countersink, the stud being formed with an enlargement, a socket seated in said 85 bore, the enlargement upon the stud seating normally against the end of said socket, and a spring within the socket and bearing against the end of the stud to hold the friction plate flat against the stile of the window 90 frame, the enlargement upon the stud serving to prevent inward bending of the friction plate at its middle.

In testimony whereof, I affix my signature, in presence of two witnesses.

STEPHEN EDWARD PARKS.

Witnesses:

T. H. ARNOLD,
ALBERT SPARROW.
